SHIP DOOR OR HATCH CONSTRUCTION AND
ADJUSTABLE RETAINING MEANS THERE-
FORWilliam R. Cochran, Philadelphia, Pa., assignor
to Heintz Manufacturing Company, a corpora-
tion of Pennsylvania

Application January 10, 1939, Serial No. 250,173

3 Claims. (Cl. 114—117)

This invention relates to a watertight closure and more particularly to an improved ship door or hatch construction having adjustable retaining means adapted to be adjusted without any necessity of dismantling either the retaining means or the door structure.

In certain types of closures, such as watertight bulk-head doors or hatches several dogging devices are sometimes located about the margin of the closure to insure a water-tight seal between the closure and its frame, the dogging members being adapted to urge the closure toward the frame and compress a gasket therebetween. The several dogging devices may be provided separate from each other or they may be interconnected for actuation by a common actuating means. After a closure of this character has been in operation a certain length of time, the gasket associated therewith tends to become set or grooved so that the closure is not completely sealed by actuation of the common actuating means through the extent of the operating movement thereof. Such condition has heretofore necessitated frequent replacement of the gasket in order to maintain the closure water-tight. Then again, water-tight closures sometimes become slightly warped so as to cause certain of the dogging devices to be subjected to greater strain than others. In order to avoid uneven strain on the dogging devices and at the same time force the entire margin of the closure with substantially even force against the frame, I have found it desirable to vary the relative positioning of the several dogging devices with respect to their mountings.

In accordance with the present invention I overcome the above difficulties by providing a ship door or hatch closure with dogging members, each of which has an adjustable feature which is simple in construction, capable of slight adjustments and easy to manipulate when adjustment is necessary. The adjustable feature of the dogging device is such that adjustments may be made either when the closure is first installed or after the gasket has become set or grooved or the closure has become slightly warped. More specifically, the dogging devices of my ship door or hatch construction are made adjustable by providing a base structure for each dogging device which is adapted to threadably receive a spindle upon which a dogging member is rotatably mounted. To lock the spindle in adjusted position the spindle is provided with a series of recesses circumferentially arranged on the threaded portion thereof which are adapted to

be engaged by a set screw carried by the base structure. The spindle is further provided with a nut keyed to the end thereof to retain the dogging member thereon, the nut providing gripping surfaces whereby the spindle may be turned for adjustment, the set screw, of course, being retracted when an adjustment is made. By use of my adjustable dogging means the pressure applied to the gasket may be adjusted at several points about the margin of the closure so as to insure proper compression of the sealing gasket for predetermined movement of the several dogging elements thereof.

One of the objects of the present invention is to provide a ship door or hatch construction having adjustable dogging means which are simple in construction and easy to manipulate when an adjustment is necessary.

Another object of the invention is to provide an improved ship door or hatch construction having dogging means mounted on the interior thereof and capable of being adjusted without any necessity of dismantling either the dogging means or the door.

The above and other objects will become apparent upon considering the following description when taken in connection with the accompanying drawing, in which:

Figure 1 is a side view in elevation of a water-tight bulkhead door with a portion of the cover-plate broken away to disclose one of the dogging members thereof;

Figure 2 is a sectional view of the door and dogging means taken along line 2—2 of Figure 1; and

Figure 3 is a sectional view taken along line 3—3 of Figure 2.

In that form of the invention chosen to illustrate a typical embodiment thereof, a portion of a water-tight door 5 is shown in the drawing in closed position on a frame 6. The door is provided with the usual hinges (not shown) and preferably with stiffening ribs 8 to reinforce the marginal stiffening member 10 and panel 12, it being understood, however, that the door may be of any other desired or convenient construction preferred insofar as the novel features of this invention are concerned. The panel 12 is secured to and extended beyond the flange 13 of the member 10 and bent back at 14 to form one side of a recess for the retention of a gasket 15. The marginal stiffening member 10 includes a flange 16 which extends at right angles to the flange 13 to complete the recess for gasket 15, a rib 18 being formed on the flange 16 for co-

operation with the bent portion 14 of the panel 12 to properly retain the gasket 15.

The frame member 6 is provided with an abutment flange 20 for engagement with the gasket 15 when the door is moved to closed position. Provided at spaced points about the frame member 6 are several cam-like wedges 22 against which the several dogging members 25 (one only being shown for purposes of illustration) are adapted to engage, whereby the door may be urged toward the frame and the gasket 15 compressed against the abutment 20.

The dogging members are made adjustable by providing each with a base structure having an internally threaded socket 26 which is secured on the interior of the door by welding the sides thereof to a base plate 28, a stiffening rib 30 and a spacer 30 which in turn is welded to the flange 16 of the marginal stiffening member 10. The base plate 28 is also welded to the panel 12 and the marginal stiffening member 10 to insure a firm support for the dogging member. A spindle 32 is provided with a threaded portion 34 adapted to be adjustably received in the socket 26. The 25 threaded portion of the spindle 32 has a series of elongated recesses 36 circumferentially arranged thereabout for engagement with a set screw 38 which extends through the flange 16, and is threadably held in a bore passed through 30 the spacer 30 and a wall of the socket 26.

The spindle 32 is provided with a shank 40 upon which a dogging member 25 is rotatably mounted, the free end of the spindle being threaded to receive a nut 44 to retain the dogging member in operative position. The dogging member is provided with an arm 46 which supports a roller 48, and a second arm 50 to which a connecting link 52 is pivotally connected at 54. The connecting link 52 may be interconnected with other dogging members and a common actuating means for movement in unison in any suitable manner, for example as disclosed in the copending application of A. L. Lambert, Serial No. 170,523, filed October 23, 1937. When the dogging member 25 is revolved clockwise by movement of the link 52 the roller 48 is moved through an arcuate path into engagement with the cam surface 22 located on the frame 6. The inclination of the cam surface 22 when engaged by the roller 48 operates to force the closure toward the abutment 20 whereby the gasket 15 is compressed to provide a water-tight seal.

The nut 44 is keyed to the spindle as indicated at 56 so that when it is desirable to adjust the 55 position of a dogging member relative to the gasket such adjustment may be made by retracting the set screw 38 to clear the ridges between adjacent recesses 36, and turning the spindle 32 in the direction desired by engaging the nut 44 with a wrench inserted through an opening 57 in the cover 58. The inclination of the threads of the threaded portion 34 and socket 26 are such that slight adjustments may be made by turning the spindle as little as the distance between 60 adjacent recesses 36. In this way very slight changes may be made by adjusting the relative positioning of the rollers 48 with respect to the gasket 15. This is important since closures provided with interconnected actuating means such, 65 for example, as that disclosed in the copending application of A. L. Lambert referred to above, the roller of each dogging member is swung through a predetermined arc by the common actuating handle. Thus, in order to increase or 70 equalize the clamping pressure of the several 75

dogging members, it is important that each dogging member be capable of proper adjustment.

It is recognized that the novel dogging means of this invention may be applied to the frame instead of the closure, also that many changes 5 in the construction thereof may be made. For example, the socket in which the spindle is threadably received may be mounted on or made integral with the frame if such were desired. Many modifications of my invention thus being 10 possible, it is to be understood that the form of the invention herein shown and described is intended to be illustrative of a typical embodiment of the invention and is not intended to limit the scope thereof.

I claim:

1. A ship door or hatch construction comprising a panel and a marginal stiffening member, a plurality of dogging means mounted on said door adjacent the marginal edges thereof for 20 rotation in a plane parallel to said panel, a second panel spaced from said first panel and cooperating with said first panel and said marginal stiffening member to define a hollow structure normally enclosing said dogging means, said hollow structure having spaced restricted openings in the marginal edges thereof adjacent each dogging means respectively, common actuating means for said dogging means adapted to rotate said dogging means about their pivots outwardly 25 through said restricted openings in the marginal edges of said door into engaging relation with a frame member or inwardly into a concealed position between said panels as desired, adjustable mountings for said dogging means each including a socket mounted within the confines of said door between said panels and adjacent said marginal stiffening member, a spindle threadably receivable in each said socket, means accessible through the said restricted openings respectively 30 for turning each spindle in its socket and a set screw threadably received in a wall of each said socket and extended through an opening in said stiffening member for holding said spindle in adjusted position.

2. A ship door or hatch construction comprising a panel provided with a marginal stiffening member extending inwardly from the face thereof, a second panel spaced from the first panel and cooperating therewith and with said stiffening member to provide a hollow structure, said structure having a plurality of restricted marginal openings, a plurality of dogging members mounted on the interior of said door, one adjacent each of said marginal openings, mechanism 55 operatively connected to said dogging members for actuating the dogging members outwardly through said openings for engagement with a frame, and inwardly through said openings to concealing position between said panels, and 60 means for adjusting said dogging members without removing either panel, comprising a mounting for each dogging member located adjacent its respective marginal opening, and means accessible by a tool through said opening for adjusting the mounting for the dogging member relative to said panels.

3. A ship door or hatch construction comprising a panel provided with a marginal stiffening member extending inwardly from the face thereof, a second panel spaced from the first panel and cooperating therewith and with said stiffening member to provide a hollow structure, said hollow structure having a plurality of restricted marginal openings, a plurality of dogging mem- 75

bers pivotally mounted on the interior of said door for pivotal movement outwardly through said marginal openings in a plane substantially parallel to said panels to engage a frame and inwardly through said marginal openings for concealment between said panels, a mounting for each of said dogging members located adjacent the said marginal opening corresponding thereto, means associated with each mounting and acces-

sible by a tool through the said opening for adjusting the dogging member relative to the panels, and means associated with each mounting and accessible for manipulation from the outside of said hollow structure for maintaining each said dogging member in a given adjusted position. 5

WILLIAM R. COCHRAN.
